CLAIM

The ornamental design for a container for helical barbed tape, as shown and described.

DESCRIPTION

FIG. 1 is a perspective view of a container for helical barbed tape showing my new design;

FIG. 2 is a top plan view thereof;

FIG. 3 is a front elevational view thereof; the rear elevational view being a mirror image thereof;

FIG. 4 is a right side elevational view thereof; the left side elevational view being a mirror image thereof; and,

FIG. 5 is a bottom plan view thereof.

FIG.1

FIG.2

FIG.4

FIG.5

FIG.3
